UNITED STATES PATENT OFFICE.

WALTER LAWTON, OF WINTHROP, MASSACHUSETTS.

COAL-ELEVATOR.

SPECIFICATION forming part of Letters Patent No. 326,129, dated September 15, 1885.

Application filed February 11, 1885. (No model.)

To all whom it may concern:

Be it known that I, WALTER LAWTON, of Winthrop, in the county of Suffolk and State of Massachusetts, have invented certain new and useful Improvements in Coal-Elevators, 5 of which the following is a specification.

This invention has for its object to provide certain improvements in apparatus for elevating coal from the holds of vessels or other receptacles, and delivering the same at a point at one side of the vessel or receptacle by a single endless series of elevator-buckets.

The invention also has for its object to provide improved means for raising and lowering 15 the series of elevator-buckets to accommodate them to the height of the coal in the vessel, and to the rise and fall of the tide.

The invention also has for its object to provide means whereby the lower portion of the 20 series of buckets can be moved laterally, so as to reach different parts of the hold or receptacle from which the coal is taken.

To these ends my invention consists in the 25 improvements which I will now proceed to describe and claim.

Of the accompanying drawings, forming a part of this specification, Figure 1 represents a side elevation of an apparatus embodying my improvements and a section of a vessel. 30 Fig. 2 represents an enlarged detail. Fig. 3 represents a modification. Fig. 4 represents a perspective view of a part of the apparatus.

The same letters of reference indicate the 35 same parts in all the figures.

In carrying out my invention I provide an endless series of scoops or buckets, *a*, connected by links or other suitable devices, so as to be capable of moving over two drums or rollers, *b b'*. The buckets and their drums *b b'* are 40 supported by a frame composed of two parts or sections, 2 3. The section 2 is straight and enters the vessel or receptacle from which coal is to be taken, while the section 3 is curved and extends from the upper end of the section 45 2 over the vessel or receptacle to an elevated point at one side of the vertical space over said receptacle. The drums *b b'* are journaled, respectively, in the upper end of the section 3 and in the lower end of the section 2, and the 50 series of buckets are caused by the described form of the supporting and guiding frame to

raise the coal from the vessel and conduct it to an elevated point at one side of the vessel, where it is discharged into a suitable chute by the tipping of the buckets as they approach and pass over the upper drum, *b*. A single series of buckets is thus enabled to elevate the coal and carry it laterally, thus performing the service for which two separate devices have been heretofore required—viz., a series 55 of elevating-buckets, and a series of conveyers or pans to receive the coal from the buckets and conduct it laterally to the point of discharge. By my improvement, therefore, the apparatus is materially simplified and cheap- 60 65 ened.

The frame 2 3 is provided with parallel guide rails or rods *c c*, (shown in Fig. 2,) between which run anti-friction rolls *d d*, journaled on the buckets *a*, said rails and rolls enabling the 70 buckets to move with the minimum of friction, particularly on the curved section of the frame. I prefer to interpose pans *e e* between the buckets *a a*, said pans having end walls or flanges, *e' e'*. The pans and their flanges receive 75 a part of the coal from the buckets when they tip in approaching the upper end of the section, and thus prevent the scattering and loss of the coal.

The frame 2 3 is preferably supported by a 80 vertically-movable frame or elevator, *g*, to which the section 3 is attached. The elevator is partially counterbalanced by a weight, *h*, suspended by a chain, *i*, which is attached to the elevator and passes over suitably-arranged 85 pulleys journaled in fixed supports, from the elevator to the weight, the object being to have the elevator and its attachments somewhat heavier than the weight, so that it will descend automatically to accommodate the 90 buckets to the height of the coal, and will be raised by the vessel when the tide is rising. The elevator with its attachments thus counterbalanced may be readily raised by the attendants when the buckets are to be entirely 95 withdrawn from the vessel.

The engine or other power which is used to impel the buckets *a* is supported by the elevator *g*, and a shaft, *k*, driven by the engine or motor, is connected by a chain or belt, *l*, 100 with a sprocket wheel or pulley, *m*, on the drum *b*, the drum being thus rotated and

caused to impel the buckets. Said drum is octagonal or of equivalent form, each side of the drum being of about the same width as each bucket and of each intermediate pan, so that the drum is engaged positively with the series of buckets.

Steam may be generated on the elevator or may be conveyed to the engine from a stationary boiler through a flexible pipe.

10 The lower section, 2, is connected to the upper section by a pivot, *n*, so that the said lower section is adapted to be moved laterally, and thus enable the buckets to reach different parts of the hold or receptacle containing the 15 coal.

o represents a frame or structure in which the elevator *g* is located. Said structure has a recess, *p*, formed to receive the elevator when the buckets *a* are not in use. The bottom 20 of the elevator has wheels *q*, which enable the elevator to be moved into and out of said recess, the wheels bearing on tracks *r* below the recess.

*b*² *b*² represent anti-friction rollers on the 25 elevator, bearing against vertical guides forming parts of the frame *o*.

Fig. 3 shows a modification in which a secondary frame, *s*, is connected to the elevator by two vertical bolts, *t t*. The curved section 30 3 is attached to the frame *s* instead of to the elevator. When one of the bolts *t* is removed, the other bolt constitutes a pivot on which the frame *s* may swing horizontally to move the frame 2 3 with the elevator-buckets away 35 from their operative position and place said frame against the side of the structure *r*, so that it will be out of the way. When this modification is employed, the elevator will not be made movable into the recess.

40 It is obvious that the frame 2 3 may be attached to a support which is not movable vertically, or may be supported by a scow or vessel. The section 2 may be rigidly attached to the section 3 instead of being pivoted there- 45 to, if preferred.

a' *a*' represent rollers pivoted to the section 3 between the ends of the rails *c* *c* on the two sections, to support the rollers *d* at the open spaces between the ends of said rails.

50 As it is desirable to unload a vessel from two hatches at the same time, to prevent straining of the hull by an unequal distribution of weight, I provide two of the endless series of buckets and their supporting and guiding devices above described.

The supporting devices of one of the series of buckets are made movable to enable the distance between the two series of buckets to be varied, and thus enable the series of buckets to enter hatchways at different distances apart. 60

I claim—

1. An endless series of elevator-buckets, combined with a supporting and guiding frame formed to conduct the ascending or loaded buckets vertically and laterally from the 65 space over the receptacle from which material is taken from the buckets, and to continuously support said loaded buckets, as set forth.

2. An endless series of elevator-buckets, combined with a supporting and guiding frame 70 composed of the curved section 3, attached to a support, and the section 2, pivoted to the lower end of the curved section, as set forth.

3. The combination of the vertically-movable frame or elevator, the guiding-frame 2 3, 75 attached thereto, and the endless series of elevator-buckets supported and guided by said frame, as set forth.

4. The curved guiding-frame, combined with the endless series of elevator-buckets and the 80 intermediate pans, as set forth.

5. The curved guiding-frame having parallel rails *c* *c*, combined with the endless series of buckets having rollers *d* *d*, as set forth.

6. The vertically-movable elevator supporting 85 the series of buckets and their guiding-frame, and provided with a motor which moves with the elevator, whereby said buckets are impelled, as set forth.

7. The elevator supporting the bucket-guiding frame 2 3, and having wheels *q*, combined with the recess *p*, adapted to receive the elevator, as set forth.

8. The sections 2 3, having the guide rails *c* *c*, and rollers *a*' *a*' between the proximate ends 95 of the rails, combined with the endless series of buckets having rollers *d*, as set forth.

9. The vertically-movable elevator supporting 100 the series of buckets and their guiding-frame, and provided with anti-friction rolls *b*', combined with vertical guides on which said rolls bear, as set forth.

In testimony whereof I have signed my name to this specification, in the presence of two subscribing witnesses, this 7th day of February, 105 1885.

WALTER LAWTON.
